DRAFT REGULATOR

John W. Miller, Lansing, Mich., assignor to Motor Wheel Corporation, Lansing, Mich., a corporation of Michigan

Application June 30, 1944, Serial No. 542,875

14 Claims. (Cl. 236—45)

1

This invention relates to automatic draft regulators for combustion apparatus.

The invention constitutes an improvement in draft regulators of the type shown in Letters Patent to Don Jones No. 2,079,804 granted May 11, 1937, and No. 2,176,217 granted October 17, 1939, and in Letters Patent No. 2,194,608 granted to John W. Miller on March 26, 1940.

The principal object of the present invention is to provide a draft regulator which is of more simple and economical construction than previous regulators.

Another object is to provide a novel adjusting mechanism for the control weights on such regulators.

A still further object is to provide novel means for attaching the control weight to the draft regulator blade.

These objects will more fully appear in the following specification when read in connection with the accompanying drawings, wherein:

Figure 1 is a fragmentary front elevational view of a draft regulator embodying the invention;

Figure 2 is a cross-sectional view taken on substantially the line 2—2 of Figure 1;

Figure 3 is a fragmentary cross-sectional view taken on substantially the line 3—3 of Figure 1 (with knob 24 shown in dotted line position of Figure 1);

Figure 4 is an oblique projectional view of the cam sleeve; and

Figure 5 is a fragmentary cross-sectional view taken on substantially the line 5—5 of Figure 1.

The drawings illustrate an automatic draft regulator comprising a damper blade 10 pivotally mounted on a pivot 11 in a collar or frame 12. The collar 12 is held in the open end of a pipe 13 attached to the flue outlet of a combustion chamber (not shown). The pivot 11 is located a substantial distance above the center of the blade so that a difference in air pressure between that in the flue outlet and the outside atmosphere, caused by the draft in the flue outlet, tends to swing the lower part of the damper inward and the upper part outward, thereby admitting air to the flue. The resistance to such swinging movement can be regulated by a control unit, indicated by numeral 14, mounted on the damper blade as will more fully appear presently.

The damper blade 10 is a sheet metal stamping of circular shape provided with integral ribs 15 to stiffen the same. It is also provided with an indentation or pocket 16, the purpose of which will appear presently. Some distance above the center of the blade are oppositely pressed integral

2

straps to receive the pivot shaft 11. The ends of the shaft 11 are received in suitable bearings 17 in the collar 12 to permit the blade to pivot.

In the center of the indentation 16 is a circular opening 18 to receive the control unit 14. Adjacent the perimeter of the indentation 16 the metal thereof is struck out to form a plurality of tongues 19 (see Figures 1 and 5), as well as to provide slots 20, the purpose of which will appear hereinafter.

The control unit comprises a sleeve 21, a shaft 22, a weight 23, and a control knob 24 attached to the blade with the sleeve located in the opening 18. The shaft, knob and weight are rotatable and axially movable relative to the sleeve to shift the center of gravity thereof relative to the plane of the blade.

The sleeve 21 (see Figures 3 and 4 particularly) comprises a cylindrical body portion 25 having an axially extending bore 26 therethrough forming a bearing for shaft 22. Opposite axial extremities of the body portion 25 are shaped as helical cam surfaces 27 and 28 arranged in parallel relation to each other.

25 A radial flange 29 is located intermediate the ends of the sleeve. Its outer surface is marked with numerals 1 to 9, each numeral indicating a different position of the control shaft and weight relative to the damper blade. On the back surface of the flange 29 are lugs 30 corresponding in number and location to the slots 20 in the blade 10. The lugs 30 are received in the slots to prevent relative motion of the sleeve and blade. The tongues 19, when bent down from the dotted line positions of Figure 5 to the full line positions, hold the flange 29 on the blade.

30 The weight 23 may be made of any suitable heavy material. It has a recess 31 in its end adjacent the blade 10 deep enough to receive the part of the sleeve 21 extending through the blade, so that the weight may be moved into juxtaposition with the blade. A pin 32 extends through a side wall of the recess adjacent its open end into the shaft 22 to hold the weight on the shaft. The pin 32 contacts the cam surface 21 and acts as a cam follower, as will become apparent presently.

35 The knob 24 on the other end of the shaft 22 can be of any shape, but preferably it is shaped like a pointer (see Figure 1) so that it will cooperate with the numerals on the flange 29 to indicate settings of the shaft. The knob is fixedly attached in any suitable manner to the shaft 22. A deep recess 33 is formed in the knob 24 parallel to the shaft 22. In the recess is a pin 35 and a spring 34. The spring 34 tends constantly

to separate the pin 35 and knob 24 and as the pin contacts the cam surface 28, the shaft 22 and weight 23 are pulled outwardly so that the cam follower 32 is always in engagement with the cam surface 27.

From the foregoing it will be evident that as the knob 24 is rotated, the weight 23 is moved toward or away from the plane of the blade. When the weight is farthest from the blade it offers its greatest resistance to tilting of the blade about its pivot, and a considerable difference in pressure between the interior and exterior of the flue outlet is required to swing the blade to its open position, and thus a relatively high draft can be maintained in the flue. On the other hand, when the weight is nearest the blade it offers little or no resistance to pivotal movement of the blade, and the draft in the flue is appreciably lowered. The weight can move into the indentation 16 and thus bring the center of gravity of the entire control unit into the plane of the blade, if desired.

The particular construction of the control unit permits of economical fabrication. The weight and sleeve can be unmachined die castings, while the knob can be molded plastic, if desired. No machining of threads or slots is required.

Also, the cam arrangement is such that the control unit will not become inoperative, or difficult to operate, because of carbon deposits thereon. Such deposits have affected previous constructions. No lubrication is necessary.

The scope of the invention is indicated in the appended claims.

I claim:

1. A draft regulator comprising a damper blade pivotally mounted in a frame, and means for varying the resistance of the damper blade to pivotal movement comprising a sleeve positioned in spaced relation to the pivot axis and extending through the blade at an angle to the plane thereof, one axial extremity of said sleeve having a substantially helical cam surface, a shaft mounted in said sleeve for longitudinal and rotary movement relative thereto, a cam follower fixedly attached to said shaft and engaging said cam surface whereby rotation of said shaft causes movement of the shaft axially of said sleeve, and spring biased means attached to said shaft and engaging the opposite axial extremity of said sleeve to maintain contact between said cam follower and said cam surface.

2. A draft regulator comprising a damper blade pivotally mounted in a frame, and means for varying the resistance of the damper blade to pivotal movement comprising a sleeve positioned in spaced relation to the pivot and extending through the blade at an angle to the plane thereof, one axial extremity of said sleeve having a cam surface, a shaft mounted in said sleeve for longitudinal and rotary movement relative thereto, a weight attached to said shaft adjacent said cam surface, a knob attached to said shaft adjacent the opposite end of said sleeve, a cam follower rigidly attached to said shaft and engaging said cam surface, and spring biased means attached to said knob and engaging the opposite axial extremity of said sleeve whereby rotation of said shaft causes axial movement thereof relative to said sleeve.

3. A draft regulator comprising a damper blade pivotally mounted in a frame, and means for varying the resistance of the damper blade to pivotal movement comprising a sleeve positioned in spaced relation to said pivot and extending

through the damper blade at an angle to the plane thereof, opposite axial extremities of said sleeve having parallel cam surfaces, a shaft rotatably mounted in said sleeve for rotary and longitudinal movement relative thereto, and means attached to said shaft adjacent opposite extremities thereof engaging said cam surfaces, whereby rotation of said shaft causes axial movement of said shaft and a shifting of the center of gravity of said shaft relative to the plane of the blade.

4. A damper regulator comprising a damper blade pivotally mounted in a frame, and means for varying the resistance of the damper blade to pivotal movement comprising a sleeve positioned in spaced relation to the pivot and extending through said blade at an angle to the plane thereof, opposite axial extremities of said sleeve having parallel cam surfaces, a shaft extending through said sleeve for rotatable and longitudinal movement relative thereto, a weight attached to one end of said shaft, an actuating knob attached to the other end of said shaft, and means on said weight and said knob engaging the adjacent cam surfaces on said sleeve whereby rotation of said knob causes axial movement of said shaft, weight and knob relative to said blade.

5. A draft regulator as defined in claim 4 wherein said weight is provided with an axially extending recess adapted to receive a portion of said sleeve in one position of said weight, and the means on the weight engaging the adjacent cam surface consists of a pin extending through a wall of said recess and fixed to said shaft.

6. A draft regulator as defined in claim 4 wherein the means on the knob engaging the adjacent cam surface comprises an axially movable pin seated in a recess in said knob and a spring in said recess biasing said pin toward said sleeve.

7. A draft regulator for combustion apparatus comprising a damper blade pivotally mounted in a frame on a pivot substantially in the plane of the damper blade, and means for varying the resistance of the damper blade to pivotal movement comprising a sleeve positioned in spaced relation to the pivot and extending through said blade at an angle to the plane thereof, opposite axial extremities of said sleeve having parallel cam surfaces, a shaft extending through said

50 sleeve and rotatable therein, a weight attached to one end of said shaft, said weight having a recess therein adapted to receive one end of said sleeve in one position of said weight, a pin extending through a wall of said recess and fixed to said shaft, said pin engaging the adjacent cam surface on said sleeve, a knob on the other end of said shaft, a pin mounted in a recess in said knob and movable axially thereof, and a spring in said last named recess for biasing said pin toward the adjacent extremity of said sleeve.

8. A draft regulator for combustion apparatus comprising a damper blade pivotally mounted in a frame on a pivot substantially in the plane of the damper blade, and means for varying the resistance of the damper blade to pivotal movement comprising a sleeve in spaced relation to the pivot and extending through the blade at an angle to the plane thereof, said sleeve having a radial flange thereon intermediate its ends juxtaposed to said blade, a plurality of recesses in said blade, a plurality of lugs on said flange seated in said recesses, and a tongue struck from said blade and engaging the surface of the flange remote from the blade for holding the flange in said juxtaposed relation to the blade.

9. In a draft regulator, the combination with a damper blade of counter balancing means for the same comprising a shaft extending through the blade at an angle to the plane thereof, said shaft being supported by the blade for rotatable and longitudinal movement relative to the blade, a cam member supported by the blade and disposed in concentric relation to the shaft on one side of the blade, said cam member having a substantially helical cam surface, a cam follower supported by the shaft for rotation therewith and adapted to engage said cam surface, and spring means carried by the shaft on the opposite side of the blade from the cam follower for biasing the shaft longitudinally to hold the cam follower against the cam surface.

10. The combination defined in claim 9 wherein said cam follower is carried by a counterbalancing weight secured to the shaft.

11. The combination defined in claim 9 wherein said spring means is carried by an operating knob secured to the shaft.

12. The combination defined in claim 9 wherein a second cam member is supported by the blade on the side thereof adjacent the spring means and the spring means cooperates with said second cam member for holding the cam follower against the said first mentioned cam member.

13. In a draft regulator, the combination with 30

a damper blade of counterbalancing means for the same comprising a shaft extending through the blade at an angle to the plane thereof, said shaft being supported by the blade for longitudinal and rotatable movement relative thereto, a cam member supported by the blade in concentric relation to the shaft on one side of the blade, said cam member having a substantially helical cam surface, a cam follower carried by the shaft and adapted to engage said cam surface, and spring biased means carried by the shaft on the opposite side of the blade from the cam follower, said spring biased means being arranged to act against a contact member carried by the blade to hold the cam follower against the cam surface.

14. The combination defined in claim 13 wherein said contact member is a cam and the spring biased means includes a cam follower resiliently pressed against said cam.
